UNITED STATES PATENT OFFICE.

WILLIAM H. ELSTON, OF MARSHALL, MICHIGAN.

IMPROVEMENT IN CARBURETERS.

Specification forming part of Letters Patent No. 136,228, dated February 25, 1873.

To all whom it may concern:

Be it known that I, WILLIAM H. ELSTON, of Marshall, in the county of Calhoun and State of Michigan, have invented an Improved Carbureter, of which the following is a specification:

My invention relates to that class of carbureters in which a rotary cylinder is employed to force air into and through a tank or receiver containing gasoline; and the invention consists in the peculiar construction of the air-forcing cylinder and the regulating-valve in the tank, as hereinafter described, whereby machines of this class are simplified and improved, and rendered capable of easy operation, without requiring any very particular management.

In the drawing, Figure 1 is a longitudinal central section of a cylinder and tank embodying my improvements, the regulating-valve being in elevation, and the plane of section of the cylinder being indicated by the line xx , Fig. 2. Fig. 2 is an end view of the cylinder, the outer and inner heads at one end being removed. Fig. 3 is also an end view of the cylinder, showing the same end as in Fig. 2, but with only the outer head removed, the inner head being in place. Fig. 4 is a view of the opposite end of the cylinder from that shown in Figs. 2 and 3, the outer head being removed. Figs. 5 and 6 are views of the opposite ends of the cylinder with the outer heads removed, representing modifications to be hereinafter described; and Fig. 7 is an end view of the valve, also representing a modification.

Similar letters of reference indicate like parts in the several figures.

A represents the horizontal air-forcing cylinder, having hollow journals, which are fitted in bearings in any suitable supporting framework, aa . The cylinder is divided, by partitions or inner heads $c d$, into a main central space, and chambers $f g$ at the ends. The central space is subdivided into three compartments, $e e^1 e^2$, by means of horizontal wings $h h h$ attached to the inner circumference and the inner heads of the cylinder. These wings h do not touch each other at the central or axial line of the cylinder, and this is to permit the free circulation of water in the cylinder, for a purpose to be hereinafter

stated. There are central openings, $i i$, made in the inner heads $c d$, so that water can also circulate in the chambers at the ends of the cylinder. Each compartment, $e e^1 e^2$, communicates with the chamber g by means of an aperture, j , Figs. 1 and 3, and with the chamber at the opposite end of the cylinder by means of openings k , Fig. 2, which are the inner extremities of elbow-pipes ll , which open into the chamber f at some distance to one side of the openings k . The cylinder communicates with the tank by means of an L-shaped pipe, m , which passes loosely through the hollow journal of the cylinder, and opens upward in the chamber f , as shown in Fig. 1, said pipe being connected by means of a sliding sleeve, n , or in any other suitable manner, with the pipe o , which enters the tank at the bottom, and extends upward therein for a short distance, as shown in dotted lines, Fig. 1. On this extended end of the pipe o is fitted the regulating-valve C , which is a vertical cylinder, closed at the top and open at the bottom, and loosely fitted on the pipe, so as to easily rise and fall as the quantity of gasoline in the tank is increased or diminished.

The size of the valve and the length of the extension of the pipe must be so adapted that there will always be a space between the upper end of the pipe and the head of the valve. Perforations are formed around the lower edge of the valve, through which the air passes into the tank from the cylinder.

Air enters the cylinder through an L-shaped pipe, p , similar to that at the opposite end of the cylinder, and already described. It is very important that these pipes $m p$ be always kept in the position shown in the drawing; and for this purpose a curved arm, q , attached at one end to the pipe, and at the other adapted to enter a recess in the stationary framework, may be used. This will keep the pipe from turning. Any other suitable device may be employed. The tank B is provided with the usual pipe r , through which the gas is conducted to the burners.

Suitable driving mechanism is fitted on one of the hollow journals, by means of which a rotary motion is given to the cylinder. The inner and outer heads of the cylinder are, of course, sealed air-tight.

When it becomes necessary to replenish the

water an elbow-shaped connection or funnel is screwed onto the end of one of the pipes which enter the cylinder, said connection rising above the end of the pipe which is within the cylinder, so that the water will readily flow in.

Having thus described the construction of my improved carbureter, I will now explain its operation: The cylinder is partly filled with water to about the height indicated by the dotted lines in Fig. 1, and gasoline is poured into the tank to any height below the top of the pipe *o*. As the cylinder is revolved air enters the chamber *g* through the pipe *p*, and, passing through the apertures *j*, fills the compartments *e e¹ e²*. These compartments are rendered separate from each other by the water, which forms a seal. The revolution of the cylinder causes the apertures between the central and end chambers to be carried successively below the water and then out of the same. When the aperture is below water of course it is sealed against the passage of air. As has been stated, each compartment *e e¹ e²* has an induction and an ejection aperture; but these openings in the chambers *f g* are not in the same plane; therefore, after one of the apertures *j* between the chamber *g* and the central portion of the cylinder has passed under the water, the mouth of the elbow-shaped tube at the other end of the same compartment remains above the surface of the water, and the air contained in the compartment escapes through this pipe, which is the only opening now left. The compartments being successively filled and discharged in this manner, a constant stream of air will be forced into the valve in the tank, and thence through the gasoline, whereby it is carbureted into the upper part of the tank, which then becomes a holder, from which the burner or burners are supplied. As the quantity of gasoline diminishes the valve settles down so that it always remains sufficiently immersed.

The cylinder may be provided with four wings or partitions, *h h*, as shown in dotted lines in Figs. 5 and 6; and, instead of having openings *j j*, as represented in Fig. 3, the partition *d* may be provided with casings *s s*, (see Fig. 5,) in which are small tubes, shown in dotted

lines, opening at one end in the chamber *g* and at the other into one of the chambers *e e¹ e²*. These openings are not in the same plane, as clearly indicated by the dotted lines. The purpose of these tubes is to equalize the pressure, and thus render the cylinder steady in its motion.

When the construction shown in Fig. 5 is employed there is also a modification in the communication between the compartments *e* and the chamber *f*, as illustrated in Fig. 6. Small apertures *t* are made through the partition *e*, opening into casings or boxes *u u* located within the chamber *f*, Fig. 1. These boxes are open at *v*.

To give to the valve *C* a uniform motion slits may be made in its lower edge. (See Fig. 7.) These may be used either with or without the series of holes shown in Fig. 1.

Having thus described my invention, what I claim as new, and desire to secure by Letters Patent, is—

1. The sealed single cylinder *A*, revolving on suitable bearings and having transverse and longitudinal partitions, and the elbow-shaped inlet and outlet pipes *m p*, all arranged and operating in the manner and for the purpose set forth.

2. The inlet-openings between the chambers *e e¹*, &c., and the space *g* provided with casings *s s* and communicating-tubes, substantially as described, and as shown in Fig. 5.

3. The outlet-openings from the central chambers *e* to the forcing-head *f*, provided with casings *u* having the openings *v* and elbow-pipes *t*, substantially as described, and as shown in Fig. 6.

4. The valve *C* in the carbureting-chamber, formed with a slotted edge, constituting wings and wedge-shaped openings, as shown in Fig. 7.

To the above specification of my invention I have signed my name this 11th day of October, A. D. 1872.

WILLIAM H. ELSTON.
